UNITED STATES PATENT OFFICE.

WILLIAM GOODELL, OF MILLINOCKET, MAINE, ASSIGNOR, BY MESNE ASSIGNMENTS,
TO THE CONE BAG COMPANY, OF MADISON, MAINE, A CORPORATION OF MAINE.

PARTITION FORMING AND ATTACHING MACHINE.

1,400,876.

Specification of Letters Patent. Patented Dec. 20, 1921.

Application filed October 23, 1920. Serial No. 420,117.

To all whom it may concern:

Be it known that I, WILLIAM GOODELL, a citizen of the United States, residing at Millinocket, in the county of Penobscot and 5 State of Maine, have invented certain new and useful Improvements in Partition Forming and Attaching Machines, of which the following is a full, clear, and exact description.

10 This invention relates to machines for operating on webs and with regard to certain more specific features thereof to devices for forming inserts for paper bags or boxes and applying the inserts in such a manner 15 as to hold fragile or perishable articles within the bags or boxes and away from the side walls of the same.

The invention has for one of its objects 20 the automatic and rapid production of partitions suitably apertured and gummed, from a continuous paper roll or web, and the arrangement of the partitions in position to accept the bag.

Another object of the invention is to provide 25 means of a reliably operative character adapted to act automatically to press the partitions against the side walls of the bag at a certain point in the cycle of operation of the partition forming mechanism whereby 30 the partition or insert is caused to adhere at the gummed areas to inner surfaces of the bag.

Still another object resides in the provision 35 of means for automatically gripping the formed partition while the bag is being applied and pressed, and for automatically releasing same after the pressing operation.

Other objects will be in part obvious and in part particularly pointed out hereinafter. 40 The invention accordingly consists in the various features of construction, combinations of elements and arrangements of parts which will be exemplified by the construction hereinafter set forth and the scope of 45 the application of which will be indicated in the following claims.

In the drawings, wherein is shown one of various possible embodiments of the invention—

50 Figure 1 is a view in front elevation of the complete machine.

Fig. 2 is a sectional view taken on the line 2—2 of Fig. 1.

Fig. 3 is a view in cross section on the line 3—3 of Fig. 1. 55

Fig. 4 is a view in cross section on the line 4—4 of Fig. 3.

Figs. 5, 6, and 7 are views of the operating gears and pinions.

Fig. 8 shows the bag applied in position 60 for pressing against the gummed insert.

Fig. 9 shows the finished product in use.

Fig. 10 is a plan view of the partition formed by the machine.

Figs. 11 and 12 demonstrate the folding 65 operation.

Fig. 13 is a view corresponding to Fig. 3 showing the cutter and folder in operation.

To the end of fulfilling the above stated objects the embodiment of the invention 70 shown in the drawings comprises a machine

which is operative to automatically feed a section of paper web into position to be acted upon simultaneously by gumming and punching mechanism whereby opposite ends 75

of the section are treated with adhesive and a plurality of apertures are formed in the body of the section. With the web section

so formed and treated the machine gives a further step of feed to the web which urges 80 the section into a position where it is severed in proper length from the remainder of the web, acted upon by a folding device, and held in folded position by a gripping device

while the bag is applied and a mechanism is 85 operated to cause adherence of the section to the walls of the bag. Thereafter the gripper is released and the finished bag may be removed from the machine. During the

period that the advanced section is being 90 severed, folded, gripped, secured and released the forming and treating operations

are in effect on the next web section. By this means the bag inserts may be rapidly 95 produced and affixed by relatively unskilled operatives; there is no substantial waste of material, and the cost of production of the finished partitioned bag is relatively low.

The method of partitioning bags in this manner so that articles such for example, 100 as ice cream cones, may be held upright or away from the interior surfaces of the bag, is also a feature of the present invention.

Referring now more particularly to the drawings there is indicated at 10 the machine frame comprising standards 11, a table

12 and numerous fixed uprights and cross pieces having provision for supporting the working parts of the machine. From any suitable source of power such as an electric motor, which may if desired, be arranged on the table 12, a shaft 13 is driven. This shaft is journaled in parallel uprights 14 and 15 of a supporting member or bracket 16 which latter is fixed to the table 12. A pinion 17 fixed on the shaft 13 meshes with a gear 18 fixed on an intermediate shaft 19, the latter being journaled in the extreme upper ends of the uprights 14 and 15 of bracket 16. Fixed on the intermediate shaft is a pinion 20 which meshes with a large spur gear 21 which latter is fixed upon what may be termed a main driving shaft 22 of the machine.

The main drive shaft 22 has fixed thereon two intermittent gears or wheels 23 and 24 and a cam 25. The first of these gears is provided with diametrically opposed toothed sections 30 and 31. These two sections cause intermittent rotation of a shaft 32 through the medium of a pinion 33 which is fixed on the shaft and which is rotated substantially one-half a revolution by each of the toothed sections of the gear or wheel 23. In a manner which will be more fully set forth hereinafter the punch mechanism is operated from this intermittent gear or toothed wheel 23.

The intermittent gear or wheel 24 has a single toothed section 35 which operates periodically to rotate each of three shafts 36, 37 and 38 through pinions 39, 40 and 41 respectively. The shaft 36 controls the feed of the paper web. The shaft 37 controls the operation of the cutting mechanism, and the shaft 38 operates the pressing mechanism.

Journaled in a standard 50 is a web roll 51, the free end of which is passed between the feed rolls 52 and 53. The lower feed roll 52 has its shaft 54 journaled in slots in uprights 55 and 56. On one end of the shaft 54 is a gear 60 which is driven through a pinion 61 from the intermittently rotated shaft 36. On the opposite end of the feed roll shaft 54 there is a spur gear 62 which connects with a similar gear 63 on the shaft 64 of the upper feed roll 53. The direction of drive is as indicated by the arrows in Figs. 2, 5, 6, and 7 and the feed rolls are periodically rotated to urge the web a predetermined distance across a fixed shelf 70. A roller 71 shown in Fig. 3 above the feed roll 53 is merely for the purpose of insuring its continued engagement with the lower feed roll.

A glue pot 72 is provided in suitably fixed relation with the frame and a glue roll 73, suitably journaled in the side walls of the pot, is continuously driven from the main drive shaft 22 through the gear 21, a pinion

74, shaft 75 and the chain and sprocket, worm and worm wheel connections shown in Fig. 1 of the drawing. (See also Fig. 6.)

The gumming and punching mechanism.

With a section of the web suitably disposed across the shelf 70 and the web rolls having discontinued their feeding action, the punching and gumming devices come into operation under the control of the gears 23 and 24. The shaft 32 of the punch operating mechanism is journaled in two uprights 80 and 81 shown in Fig. 4 as fixed to the shelf 70. This shaft has secured to or formed thereon the eccentrics 82 and 83 which operate on circular punches 84 and 85. These punches are secured in a block 86 which is apertured to fit slidably on the uprights 80 and 81 and be guided by these uprights in a vertical reciprocatory movement effected by the rotation of the eccentrics. Spaced upwardly from the block 86 and connected thereto by means of four bolts 88 there is a lifting plate 87 which cooperates with the block to form a yoke for the eccentrics. Spaced downwardly from the block 86 is a presser plate and guide 90. This plate is held in spaced relation with the block by means of springs 91 and 92 arranged respectively about bolts 93 and 94. The lower ends of these bolts are tapped into the presser plate and their heads 95 and 96 determine the position of the presser plate when the punches are in their up position.

A rock shaft 100 is journaled between front and rear uprights 101 and 102 of the frame superstructure as shown in Fig. 2 and on it there are fixed two arms 103 and 104 spaced apart in the direction of feed of the web and carrying at their lower free ends loosely mounted disks 105 and 106 journaled in slots 107 in the arms. During a prolonged portion of the cycle of operation of the machine these disks bear on the continuously rotating glue roll 73 and they are constantly supplied thereby with glue from the reservoir 72.

When the shaft 32 is rotated a half turn the eccentrics 82 and 83 are given a movement through 180° and the block 86 carrying the punches is urged downwardly. The presser plate 90 is caused to bear upon the web to hold it securely in position. This plate is yieldable against the action of the springs 91 and 92 and the punch members 84 and 85 penetrate the die or fixed shelf 70 resulting in a plurality of apertures in the web. With the punches in their extreme downward position the operating shaft which carries the eccentrics is locked against further rotation during substantially one-half the revolution of the main drive shaft. With the web section thus firmly held by the presser plate and the punches in their positions of penetration the toothed section 35

130

of the gear or wheel 24 becomes effective to rotate the shaft 37 to actuate a cross-head 110 mounted upon an upright beam 111. This cross head is reciprocated once during every revolution of the main drive shaft by means of a crank connection shown at 112 in Fig. 1. A lever 113 is loosely connected to the rear of the cross-head and extends upwardly above the frame of the machine where it has a pivotal connection with an arm 114 extending from the rock shaft and keyed thereto. It will be seen, therefore, that reciprocation of the cross-head will affect the rocking of the shaft 100 which in turn will cause the disks 105 and 106 in suitably gummed condition, to roll over the web and return, thereby providing the web with gummed areas as indicated in Fig. 10 of the drawings.

20   *The cutting, folding and pressing mechanism.*

The movement of the cross-head which affects the operation of the gumming mechanism also controls the operation of a cutter C and a folder F. The cutter comprises a knife 120 carried on a pair of parallel links 121 and 122 journaled in the frame structure. The lower link 121 has a pin and slot connection with the cross-head as indicated at 123 in Fig. 1. The shelf 70 has a front knife-reinforcing wall 124 suitably apertured at 125 to permit the feed of the web. As the cross-head moves downwardly the knife is carried downwardly with a slight sheering action due to the parallel link arrangement, the return of the cross-head carries the knife to a position above the aperture 125 thereby permitting a subsequent step feed of the web.

The folder F is of inverted U shape comprising a reinforcing crutch 130 at the lower end of a link 131. This link is pivotally connected to the parallel links 132 and 133 which have their opposite ends pivotally connected to an upright of the frame structure. The lower parallel link 132 of this mechanism is connected by a link 134 to the cross-head and a downward movement of the latter causes an arcuate down movement of the folder into a position of contact with the web section that is being severed by the knife. The folder is given resiliency by means of a spring member 135 and the opposite ends 136 and 137 of this spring member are bridged by a band 138 of fabric or other pliable material. The continued movement of the cross-head causes the folder to urge the severed web portion about a partition or anvil 140 which latter is upstanding from the table 12 of the frame. The machine is timed and the parts arranged so that the folder will pick up the severed web section at the instant that it is severed from the remainder of the web, and dispose it centrally about the partition

140. Before the folder releases, a pair of gripper fingers 141 and 142 are actuated to engage the opposite ends of the severed web portion on opposite sides of the partition and hold the web section in folded position. 70 The mechanism for actuating the gripper fingers comprises a cam 25 driven from the main operating shaft 22. The cam co-operates with a cam roll 152 at the upper end of a rod 153 mounted for vertical sliding movement in the frame. The rod at its lower end has a pin and slot connection with a lever 154 fixed on a rock shaft 155 which latter has suitable bearings in the frame structure. Coil springs 156 are arranged between the frame and the lower end of the rod 153 and act to swing the lever 154 on the rock shaft to cause engagement of the gripper fingers with the web section through a link 157 and links 158 and 159 which connect with the 85 gripper fingers. The action of the springs 156 is opposed by the cam during the greater portion of its rotation but at a point just following the folding of the web section about the partition 140 the high portion 160 90 of the cam moves beyond the cam roll 152 allowing the springs to take effect thereby causing the gripper fingers to engage with opposite ends of the web section to hold same during the assembling and pressing operations. 95

Assembling and pressing.

With the web section held by the gripper fingers the machine operator applies an inverted bag after the manner indicated in Fig. 8 of the drawings. The bag is held in this position by the operator during the latter part of the cycle of operation of the machine. The toothed section 35 of the gear or wheel 24 then operates upon pinion 41 on the presser controlling shaft 38 and through a crank 170 on the end of this shaft and link 171 a lever 172 is oscillated. Two rock shafts 173 and 174 are journaled in the frame and 110 rocked by means of lever 172 and a link connection 175 between said lever and the rock shaft 174. Presser arms 180 and 181 carrying presser blocks 182 and 183 are actuated into pressing position through rocker arms 184 and 185 and the link connections 186 and 187. The pressure is sufficient to cause the insert to be attached at each end at the gummed areas to the side walls of the bag and as the machine continues its operation the presser blocks 182 and 183 are withdrawn. The gripper fingers are then separated by the cam 150 and the bag with its attached insert may be withdrawn from the partition. 120

125

Operation.

The feed rolls being driven in opposite directions from the main driving shaft cause a predetermined amount of web to be fed 130

across the die shelf 70. The punch mechanism and gumming device are then operated in the manner hereinbefore set forth. The punches and presser plate remain in their 5 downwardly actuated position during substantially one-half revolution of the main driving shaft. The second toothed section on the wheel 23 then operates the pinion 32 to further rotate the eccentrics to withdraw 10 the punches and release the presser plate from the web. With the web section thus gummed and punched the machine starts on its second cycle of operation commencing by feeding a predetermined length of web. 15 During this operation there is actuated a lifting rod 190 slidably mounted in the frame of the machine and having a finger 191 extending along the forward edge of the die shelf. This lifter is operated by 20 means of a crank and link connection 192 the crank being fixed on the end of the shaft 54 of the lower feed roll. The parts are timed so that as the feed movement of the web takes place the finger 191 of the lifter 25 will advance forwardly and upwardly owing to the incline of a slide bearing 193. The function of this device is to lift the forward edge of the web into a position where its advance over the top of the partition 140 30 will be insured.

At the end of the second stroke of feed the punches are again operated, the web being held as formerly by the presser plate and the punches in their penetrated positions. The cross-head 110 is then operated causing the web to be severed by the knife and simultaneously contacted with by the folder and disposed about the partition 140. As the action of the glue rolls is also under 40 control of the cross-head it will be seen that the second web section is being gummed during the severing and folding operations on the first section. The reciprocation of the cross-head is substantially rapid and the 45 knife and folder are returned to their upper positions immediately the opposite ends of the web section have been gripped by the fingers 141 and 142. This enables the operator to apply the bag and as the main 50 shaft continues its rotation the toothed section 35 of the gear wheel 24 engages with the pinion 41 and operates the presser blocks 182 and 183 into and out of pressing engagement.

55 At a convenient point in the operation of the machine the second toothed section of the gear 23 operates through the pinion 33 and shaft 32 to rotate the eccentrics 82 and 83 another half turn, causing withdrawals 60 of the punches and the lifting of the presser plate 90. In the present embodiment of the invention this lifting operation takes place just prior to the actuation of the presser blocks. The punches are provided with 65 gravity strippers 150.

As many changes could be made in the above construction and as many apparently widely different embodiments of the invention could be made without departing from the scope thereof, it is intended that all 70 matter set forth in the foregoing description or shown in the accompanying drawings shall be interpreted as illustrative and not in a limiting sense.

What I claim is:

75 1. In a machine of the character described, in combination, means for feeding, punching and gumming a web section, means for severing said web section from the web, a plate, and means for folding said section on said plate in position to be acted upon, where gummed, by pressing means.

2. In a machine of the character described, in combination, means for feeding, punching and gumming a web section, means for severing said web section from the web, a plate and means for holding said section on said plate in position to be acted upon, where gummed, by pressing means.

80 3. In a machine of the character described, in combination, means for feeding, punching and gumming a web section, means for severing said web section from the web, a plate, means for folding said section on said plate in position to be acted upon, where 85 gummed, by pressing means, and a presser device adapted to act on opposite sides of said plate to cause the section to adhere to the inner walls of a container positioned over said plate and section.

100 4. In a machine of the character described in combination, means for feeding a web, means for providing an aperture in said web, means for severing an apertured section of the web from the web body, an anvil, means 105 for folding the severed web section with its opposite ends on opposite sides of the anvil, and means for attaching the opposite ends of the web section to opposite walls of a container positioned around said anvil.

110 5. In a machine of the character described, in combination, means for feeding a web step-by-step, means for punching the web and gumming certain areas, means for severing a punched and gummed section of the 115 web, means for folding the web with gummed areas on opposite sides of a fold, and pressing means intermittently operative to cause the section to adhere to opposite sides of a container positioned around said web.

120 6. In a machine of the character described, in combination, means for punching a sheet, means for gumming opposite ends of said sheet, means for folding said sheet in position to receive a container, and means for securing the sheet to the inner part of the container in such a way that the punched section thereof is spaced from the walls of the container.

7. In a machine of the character described, in combination, means for folding and holding an apertured sheet in position to be surrounded by the side walls of a container, means acting upon the sheet when in such position, for securing opposite ends of the sheet to opposite side walls of the container. 5
8. In a machine of the character described, in combination, a device for effecting intermittent feed of a web, means for severing a section from the web, an anvil member, means adapted to fold the severed section in position on said anvil member, and means intermittently coöperative with said anvil to attach opposite ends of said section to the walls of a container introduced over said anvil member. 10
9. In a machine of the character described, in combination, web-feeding means, means for temporarily holding a web section, punching and gumming devices operative to punch and gum the web section when the last said means are operative, a cutter, 20 a plate, and means for folding a cut section of web about said plate as the gumming device is operating on an uncut section. 25
10. In a machine for forming shelves and attaching them to the inner walls of paper bags, the combination with a web feeding device, of means for punching a plurality of socket apertures in a section of the web, means for gumming opposite ends of the section, means for severing the section from the web, and means for pressing the gummed 30 portions of the section against the inner walls of a bag. 35
11. In a machine for forming shelves and attaching them to the inner walls of paper bags, the combination with a web feeding device, of means for punching a plurality of socket apertures in a section of the web, means for gumming opposite ends of the section, means for severing the section from the web, an anvil, means for folding the section over the anvil, means for holding the section on the anvil after the release of 40 said section by the folding means, and means for pressing the gummed portions of the section against the inner walls of a bag. 45
12. In a machine for forming shelves and attaching them to the inside of containers, the combination of web feeding means with a clamping and punching device, means for 50 gumming opposite ends of a punched section of the web, cutting and folding means operative on an advanced web section conjointly with the operation of said gumming means on an after section, and a presser for 55 causing the cut web section to adhere at its gummed portions to a container within which it is arranged. 60
13. In a machine of the character described, in combination, web feeding rolls 65 intermittently actuated to cause a step feed of web, a combined punch and holder intermittently actuated to hold and punch a section of the web, a knife for severing the punched section at the end of its second step of feed, and means intermittently operative 70 for folding the punched section of web, and attaching same to a container, the punch and holder being operative on a second section of web during the severing and folding operations. 75
14. The method of forming and attaching shelves for bags which consists of punching and gumming a section of a continuous web, cutting the section from the web, folding the section about an anvil, positioning a bag over the anvil and folded web section, and applying pressure to the assembled bag and section opposite gummed areas of the section. 80
15. The method of attaching apertured sheets to a bag to form a shelf in said bag which consists of folding the sheet over an anvil to dispose opposite ends of the sheet on opposite sides of the anvil, positioning a bag over the anvil and folded web and 90 pressing opposite sides of the bag against opposite ends of the sheet to cause them to adhere where pressed. 95
16. In a machine of the character described, in combination, gumming, cutting and folding devices, and a reciprocatory means for simultaneously actuating all three devices, whereby one section of a web is gummed, another section folded and the two sections separated. 100
17. In a machine of the character described, an anvil, means for disposing a flexible sheet over said anvil, means intermittently actuated to fold said sheet about said anvil and return to a normal position 105 away from said anvil to permit the positioning of an open bag around said anvil, means for holding said sheet in folded position after the return of said folding means, and means intermittently actuated to press opposite side walls of the bag against opposite ends of the folded sheet. 110
18. In a machine of the character described an anvil, means for disposing a flexible sheet over said anvil, means intermittently actuated to fold said sheet about said anvil and return to a normal position away from said anvil to permit the positioning of an open bag around said anvil, means for holding said sheet in folded position 115 after the return of said folding means, and means for effecting the attachment of opposite ends of said sheet to opposite walls of said bag. 120
19. In a machine of the character described, in combination, a die shelf, an anvil, web feeding means adapted to move a web step-by-step in a forward direction relatively to said die shelf and anvil, a punch and gumming device for perforating and 125
- 65 intermittently actuated to cause a step feed 130

- 6
- gumming the web between feeding movements, a guide for insuring feed of the forward end of the web over the anvil, means for severing a punched and gummed section 5 of the web from the web body, and a folder for urging opposite ends of the web over opposite sides of the anvil; said folder being movable away from the anvil after the folding operation to permit attachment of the 10 folded web section to a bag.
20. In a machine of the character described, in combination, a die shelf, an anvil, web feeding means adapted to move a web step-by-step in a forward direction relatively to said die shelf and anvil, a punch and gumming device for perforating and gumming the web between feeding movements, a guide for insuring feed of the forward end of the web over the anvil, means 15 for severing a punched and gummed section of the web from the web body, a folder for urging opposite ends of the web over opposite sides of the anvil; said folder being movable away from the anvil after the folding operation to permit attachment of the folded web section to a bag, means for gripping the web section at the extreme opposite ends to hold same to the anvil after the release by the folder; and a presser adapted to coöperate intermittently with the anvil to press the bag against the gummed 20 portions of the web section. 70
21. In a machine of the character described, in combination, a die shelf, an anvil, web feeding means adapted to move a web step-by-step in a forward direction relatively to said die shelf and anvil, a punch and gumming device for perforating and gumming the web between feeding movements, a guide for insuring feed of the forward end of the web over the anvil, means 25 for severing a punched and gummed section of the web from the web body, a folder for urging opposite ends of the web over opposite sides of the anvil; said folder being movable away from the anvil after the folding operation to permit attachment of the folded web section to a bag, and means for gripping the web section at the extreme opposite ends to hold same to the anvil after the release by the folder. 30
22. In a machine of the character described, in combination, a die shelf, an anvil, web feeding means adapted to move a web step-by-step in a forward direction relatively to said die shelf and anvil, a punch and gumming device for perforating and gumming the web between feeding movements, a guide for insuring feed of the forward end of the web over the anvil, means for severing a punched and gummed section 35 of the web from the web body, a folder for urging opposite ends of the web over opposite sides of the anvil; said folder being movable away from the anvil after the folding operation to permit attachment of the folded web section to a bag, means for gripping the web section at the extreme opposite ends to hold same to the anvil after the release by the folder; and a presser adapted to coöperate intermittently with the anvil to press the bag against the gummed 40 portions of the web section. 65
23. In a machine of the character described, in combination, gumming, cutting and folding devices and a common actuating means for all three devices comprising a cross head and suitable connecting links, whereby one section of a web is gummed, another section folded and the two sections separated. 75
24. In a machine of the character described, in combination, gumming, cutting and folding devices actuated by a common means intermittently between step feeds of a web and having provision for gumming a web section simultaneously with the folding and severing of an advanced section of the 80 web. 85
25. In a machine of the character described, in combination, gumming, cutting and folding devices, an intermittently reciprocating cross head and connecting means 90 between the cross head and said gumming, cutting and folding devices for causing simultaneous actuation of all three devices between the step feeds of a web. 95

WILLIAM GOODELL.
